Primary Examiner — Brett Miller
Assistant Examiner — Rani J Abdallah(57) **CLAIM**

We claim the ornamental design for a product container, as substantially shown and described.

DESCRIPTION

FIG. 1 is an elevated perspective view of a product container of the present invention.

FIG. 2 is a level view of a front side of the product container of the present invention.

FIG. 3 is a level view of a rear side of the product container of the present invention.

FIG. 4 is a level view of a right side of the product container of the present invention.

FIG. 5 is a level view of a left side of the product container of the present invention.

FIG. 6 is a top plan view of a top side of the product container of the present invention; and,

FIG. 7 is a bottom-up view of a bottom side of the product container of the present invention.

The broken lines shown illustrate portions of the product container that form no part of the claimed design.

1 Claim, 4 Drawing Sheets(56)
